WATER SERVICE DEVICE

James E. Riley, Minneapolis, Minn.

Application January 3, 1939, Serial No. 249,065

4 Claims. (Cl. 137—13)

My invention relates to water service devices. It relates more particularly to shut off devices which are placed between the water main and the place to be serviced with water. The water main and the valve portion of the shut off device which is in the connection leading from the main to the place to be serviced are ordinarily placed in the ground below the frost line. Therefore if a leak should develop, it becomes necessary in making repairs for the purpose of stopping the leak, to dig down below the surface of the ground to the place where the leak has occurred. This involves a very considerable expense to the taxpayer since he is charged with the cost of the repair work. An object therefore of my invention is to reduce the liability of leaks in connection with the shut off device. In order to accomplish this desirable result, I provide three things, as follows: (1) A tight box surrounding the valve casing whereby the entrance of sand and dirt is prevented; (2) a stand pipe extending up from the valve casing which stand pipe has its upper portion in permanently sliding relation to its lower portion so that freezing of the ground cannot impose any strain on the shut off device and its connections for passage of water; (3) a closure in the upper portion of the stand pipe which requires a special tool to remove so that unauthorized persons, such as children, cannot drop any foreign material down the stand pipe.

The novel features which I believe to be characteristic of my invention are set forth with particularity in the appended claims. The invention itself, however, both as to its organization and method of operation, together with additional objects and advantages thereof, will be best understood from the following description of a specific embodiment, when read in connection with the accompanying drawings in which,

Fig. 1 is an elevational view of the device installed for use.

Fig. 2 is a fragmentary view in vertical section on the line 2—2 of Fig. 3, looking in the direction of the arrows and showing an upper closure.

Fig. 3 is a view in horizontal section on the line 3—3 of Fig. 2, looking in the direction of the arrows.

Fig. 4 is a view in horizontal section on the line 4—4 of Fig. 7, looking in the direction of the arrows.

Fig. 5 is a view in horizontal section on the line 5—5 of Fig. 7, looking in the direction of the arrows.

Fig. 6 (Sheet 2) is a view of the device largely in central vertical section.

Fig. 7 is a view of a portion of the device taken at right angles to Fig. 6.

Fig. 8 is an elevational view of the box showing in dotted lines how the two parts thereof may be separated.

Referring to the construction shown in the drawings, the numeral 10 designates the customary valve casing which contains a shut off valve having a head consisting of a square portion 12 above which is narrow portion 14 so that the valve may be readily turned by tools having differently constructed engaging ends. As shown in Fig. 6, the upper end of the valve casing is provided with screw threads 16 upon which is screwed a cup member 18 surrounding and spaced from the square portion 12 of the valve head. As usual, the valve casing 10 carries a tubular member 20 adapted to be connected by 20 a pipe with the water main and also carries a tubular member 22 adapted to be connected by a pipe with the place to be serviced.

In order to prevent the entrance of sand and dirt to the valve casing 10, I provide as part of my invention, a box 24 best shown in Fig. 8 and which is adapted to fit tightly around the valve casing 10. The box 24 has a base member 26 which carries the upstanding portion of the box. This upstanding portion is made in two parts 28 and 30. The member 28 is integrally carried by the base 26 while the member 30 is detachable and at its lower end carries a hook 32 adapted to be engaged in a slot 34 formed in the base 26. As will be apparent from Figs. 6, 7 and 8, the contiguous sides of the members 28 and 30 are notched out just sufficiently to snugly receive the tubular connections on the two opposite sides of the valve casing 10.

The two-part construction of the box 24 enables it to be readily installed around the valve casing as will be understood from Fig. 8. In order that the member 30 may be readily swung into position around the hook 32, the lower edges of the member 28 are made concave as indicated at 36 while the corresponding edges of the member 30 are made convex as indicated at 38. This not only provides for easy installation of the box around the valve casing but insures a tight enclosure therefor. Furthermore it will be noted that the upper edges of the member 28 are notched as indicated at 40 while the corresponding edges of the member 30 have projections 42 which fit into the notches 40. The members 28 and 30 below their tops are provided respectively 55

with outwardly extending flanges 44 and 46 which are provided with slots 48.

After the box 24 has been placed in tight condition around the valve casing 18 in the manner previously referred to, the lower section 50 of a stand pipe 52 is secured to the upper portion of the box. In order to do this the lower end of the section 50 is provided with diametrically opposite flanges 54 containing holes through which and through the slots 48, bolts 56 are secured.

For completing the stand pipe 52, an upper section 58 is provided, this section being shown as consisting of two parts firmly secured together 15 at 60 so that the upper section 58 is in effect an integral member.

Another very important feature of my invention will now be described. Heretofore it has been customary in devices of this character to 20 provide a stand pipe made in two sections and having their two adjacent ends telescoped and provided with a packing designed to permit the upper section to slide with relation to the lower section. This is for the purpose of preventing 25 strains on the valve casing and connections during freezing of the ground. I have found that in the course of time, the metal adjacent the packing becomes corroded so that the upper section of the stand pipe is no longer capable of 30 sliding on the lower section, the result being that strains occur which cause leakage with consequent necessity of digging down to the shut off valve and its connections. In order to overcome this difficulty, I have provided the construction 35 now to be described. The lower end of the upper section 58 is telescoped for a considerable distance over the upper end of the lower section 50. Instead of providing a packed joint between the two sections, I provide a loose telescoping 40 construction with allowance for considerable space between the telescoped portions. An outwardly extending lug 62 on the lower section 50 serves as a stop for the downward movement of the upper section 58, it being understood as 45 a matter of course that freezing of the ground has a lifting action on the upper section. In order to guide the upper section and keep it in alignment with the lower section, I provide the lower section with a number of outstanding projections 50 64 which space the telescoped portions equally from each other. As shown in Fig. 1, there is an upper circumferential row and a lower circumferential row of these projections with four of them in each row. The point of contact 55 of these projections with the upper section is very small so that there is no danger of causing them to stick by corrosive action to the upper section, but at the same time the upper section is guided and kept in alignment with the lower section.

Another feature of my invention will now be described. It is customary to provide the upper end of the stand pipe 52 with a hinged cover 66 which is very easily lifted. I have found that 65 this fact permits mischievous persons, especially children, to stuff all sorts of trash down the stand pipe with the result that the stand pipe sometimes becomes filled and should be cleaned out. Furthermore, the presence of this trash 70 increases the liability of leaks occurring, especially during freezing weather. It also sometimes happens that snow plows and trucks break off the hinged cover 66 so that extraneous material collects in the stand pipe. This trash and 75 extraneous material in the stand pipe makes it

impossible to reach the shut off valve with a tool so that it sometimes becomes necessary to dig down outside of the stand pipe before the shut off valve can be turned. In order to overcome this difficulty, I provide a closure in the upper portion of the stand pipe which can be removed only by the use of a special tool not apt to be accessible to unauthorized persons. Referring to the particular construction shown in Figs. 1, 2 and 3, I secure a ring 68 in the upper portion 10 of the stand pipe by means of a screw plug 70 extending through the stand pipe and having its head inside of the ring. The ring is internally threaded to receive a threaded plug 72, the head of screw plug 70 preventing the plug 72 from 15 being turned entirely through the ring. The upper surface of the plug 72 carries a projection 74 of special configuration so that a special tool is required to remove the plug. As shown, this projection is pentagonal or five sided. The ring 20 68, the screw plug 70 and the plug 72 are made of non-corrodable material, such as brass, which gives these parts a very long life without danger of getting out of place, as by dropping to the 25 bottom of the stand pipe.

The operation and advantages of my invention will be readily understood in connection with the foregoing description and the accompanying drawings. It is to be noted that the lower end of the stand pipe fits snugly around the 30 upper portions of the box members 28 and 30 and that these upper portions fit snugly around the cup member 18. Furthermore the box members 28 and 30 when assembled fit snugly around the tubular projections extending out from the 35 two opposite sides of the valve casing. Therefore, entrance of sand and dirt to the valve casing and into the lower portion of the stand pipe containing the head of the shut off valve is effectively prevented. The construction which I have 40 provided not only greatly lessens the liability of leaks occurring adjacent the shut off valve, but also greatly decreases the necessity of digging down to the shut off valve, which is a difficult and messy job, especially when the ground is 45 saturated with water or frozen, it being understood as a matter of course that in cold climates, it is necessary to place the shut off valve a considerable distance below the surface of the ground. My construction therefore often saves 50 considerable expense to the taxpayer, since it guarantees a clean box and ability to reach the shut off valve with a tool inserted down the stand pipe.

The tight closure in the upper portion of the 55 stand pipe has another very important purpose which is during thawing of the ground, water is prevented from running down the stand pipe and then freezing solid therein. If this should occur, then in order to reach the shut off device, 60 it is necessary to dig down to this device. But since the special closure just referred to is positioned near the top of the stand pipe, only a shallow layer of ice can form thereover and this can be readily removed, as by chiseling.

I claim:

1. A stop box for underground valves, comprising a bottom wall and two vertical members adapted to surround and tightly enclose the valve casing, said vertical members being constructed 70 to fit snugly around the pipe connections from opposite sides of the valve, one of said vertical members being fixedly carried by said bottom wall, and means for detachably securing the other vertical member to said bottom.

2. A stop box for underground valves, comprising a bottom wall formed with a slot, two vertical members adapted to surround and tightly enclose the valve casing, one of said members being fixedly carried by said bottom wall, and a projection on the lower end of the other of said members adapted to be detachably engaged in said slot.

3. A stop box for underground valves, comprising a bottom wall formed with a slot, two vertical members adapted to surround and tightly enclose the valve casing, one of said members being fixedly carried by said bottom wall, and a hook on the lower end of the other of said members adapted to be detachably engaged in said slot, the adjacent edges of said members being

curved to permit the detachable member to swing upon said hook into close engagement of said edges with the fixed member and with one side of the pipe connections to the valve.

4. A stop box for underground valves, comprising members adapted to surround and tightly enclose the valve casing, a stand secured to said members provided with two sets of projections spaced apart and with their outer margins in a common cylindrical plane forming conjointly guide members, a stop on said stand below said guide members, and an upper pipe section telescoped over said stand with its inner surface in contact with said projections and with its lower end engaging said stop.

JAMES E. RILEY.
